UNITED STATES PATENT OFFICE.

ALEXANDER HANSON, OF CHICAGO, ILLINOIS.

SPRING-STILT.

No. 822,448.

Specification of Letters Patent.

Patented June 5, 1906.

Application filed July 12, 1905. Serial No. 269,281.

To all whom it may concern:

Be it known that I, ALEXANDER HANSON, a citizen of the United States, residing at Chicago, in the county of Cook and State of Illinois, have invented certain new and useful Improvements in Spring-Stilts, of which the following is a specification.

My invention relates to improvements in spring-stilts; and the object of my improvements is to provide an amusement device to be secured to the feet while running foot-races at picnics or similar places of amusement.

In the drawings, Figure 1 is a top plan view of one of my spring-stilts; Fig. 2, a side view of same; Fig. 3, a top plan view of a spring-stilt of modified construction; and Fig. 4 a side view of the latter.

Referring to the drawings in detail, a represents a plate made, preferably, of wood and provided with two openings *a'*, extending crosswise therethrough and adapted to receive straps for fastening the plate to the foot.

Rigidly secured to the rear end of the plate by means of screws *b* is a metal rim *c*, which projects above the plate and provides a flange to engage the heel of the shoe or boot and prevent the plate from sliding forward under the foot. One end of a coil-spring *d* is secured to the under side of the plate by means of bolts *e*. An annular groove is preferably formed in the under side of the plate to receive the end of the spring. The outer end of the spring is adapted to rest on the

ground when the plate is secured to the foot. The springs are preferably made strong enough to support the weight of the user without collapsing but partially.

In operation one of the stilts is secured to each foot by means of straps inserted in the openings *a'* and buckled over the toes and instep. The user then attempts to run a race with one or more other persons having the same stilts on his or their feet, and the awkward movements of the runners is adapted to provoke laughter and amusement for the lookers-on.

In the modified construction shown in Figs. 3 and 4 two coil-springs instead of one are secured to the bottom of the plate and have their outer ends connected by means of a metal strap *f*, which has its ends bent around the lower coil of the spring.

Having thus described my invention, what I claim as new, and desire to secure by Letters Patent, is—

In a device of the character described, a plate adapted to be secured to the sole of the foot, and a coil-spring, having one end connected with the under side of the plate and having its opposite end adapted to rest on the ground.

In testimony whereof I affix my signature in presence of two witnesses.

ALEXANDER HANSON.
